US00D681640S

(12) **United States Design Patent**
Aoki et al.

(10) **Patent No.:** US D681,640 S
(45) **Date of Patent:** ** May 7, 2013

(54) **STORAGE MEDIUM**

(75) Inventors: **Yoshitaka Aoki**, Tokyo (JP); **Takashi Sogabe**, Tokyo (JP); **Shinjiro Komatani**, Tokyo (JP)

(73) Assignee: **Sony Computer Entertainment Inc.**, Tokyo (JP)

(**) Term: **14 Years**

(21) Appl. No.: **29/371,615**

(22) Filed: **May 24, 2011**

(30) **Foreign Application Priority Data**

Dec. 3, 2010 (JP) D2010-028894

(51) **LOC (9) Cl.** **14-02**

(52) **U.S. Cl.**

USPC **D14/436**

(58) **Field of Classification Search** D14/435-438, D14/478-480; 235/441, 443, 487, 492, 493, 235/495; 361/737, 679, 752, 736, 728, 796, 361/797, 729, 730, 725-727; 257/678, 679, 257/693, E23.064; 439/946, 948, 159; 174/250, 174/260, 52.1, 52.2; 710/300-303; 438/121

See application file for complete search history.

(57) **CLAIM**

The ornamental design for a storage medium, as shown and described.

DESCRIPTION

FIG. 1 is a perspective view of a storage medium showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof

FIG. 8 is a perspective view of another embodiment of a storage medium showing our new design;

FIG. 9 is a front elevational view;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

Portions in broken lines are for illustrative purposes only and form no part of the claimed design.
